DESIGN FOR A LIGHTER

Albert A. Hellman, Los Angeles, Calif., assignor to Meyer Lublin, Los Angeles, Calif.

Application April 7, 1945, Serial No. 118,890

Term of patent 14 years

(Cl. D48—27)

To all whom it may concern:

Be it known that I, Albert A. Hellman, a citizen of the United States of America, residing in the city of Los Angeles, in the county of Los Angeles, State of California, have invented a new, original, and ornamental Design for a Lighter, of which the following is a specification, reference being had to the accompanying drawing, forming a part thereof.

Fig. 1 is a front perspective view of a lighter in closed position showing my new design;

Fig. 2 is a rear perspective view;
Fig. 3 is a perspective view similar to Fig. 1 showing the lighter in open position;

Fig. 4 is a top plan view;
Fig. 5 is a front elevational view; and
Fig. 6 is an end elevational view.

I claim:

The ornamental design for a lighter, substantially as shown.

ALBERT A. HELLMAN.
